Primary Examiner — Cynthia Underwood*(74) Attorney, Agent, or Firm* — George P. White(57) **CLAIM**

The ornamental design for a cover, keyboard, and stand for an electronic display, as shown and described.

DESCRIPTION

FIG. 1 shows a front perspective view of a cover, keyboard, and stand for an electronic display in an open state;

FIG. 2 shows a front perspective view thereof in a closed state;

FIG. 3 shows a rear perspective view thereof in a detached state;

FIG. 4 shows a rear perspective view thereof;

FIG. 5 shows a right side view thereof in a closed state;

FIG. 6 shows a left side view thereof in a closed state;

FIG. 7 shows a front view of thereof in a closed state;

FIG. 8 shows a back view thereof in closed state;

FIG. 9 shows a top view thereof in a closed state;

FIG. 10 shows a bottom view thereof in a closed state; and,

FIG. 11 shows a front perspective view thereof in a detached state.

The broken lines are included for illustrative purposes only and form no part of the claimed design.
